Primary Examiner — Clare E Heflin*(74) Attorney, Agent, or Firm* — King & Spalding LLP**CLAIM**

The ornamental design for an edgelit garage luminaire, as shown and described.

DESCRIPTION

FIG. 1 is a top perspective view of an edgelit garage luminaire, showing my new design;

FIG. 2 is a bottom perspective view thereof;

FIG. 3 is a bottom plan view thereof;

FIG. 4 is a top plan view thereof;

FIG. 5 is a left-side elevation view thereof;

FIG. 6 is a rear elevation view thereof;

FIG. 7 is a front elevation view thereof; and,

FIG. 8 is a right-side elevation view thereof.

The broken lines shown represent unclaimed subject matter and form no part of the claimed design.
